UNITED STATES PATENT OFFICE.

EMILE GIRARDEAU AND JOSEPH BETHENOD, OF PARIS, FRANCE.

SYSTEM FOR PRODUCING HIGH-FREQUENCY CURRENTS.

1,101,491.

Specification of Letters Patent. Patented June 23, 1914.

Application filed June 4, 1913. Serial No. 771,743.

To all whom it may concern:

Be it known that we, EMILE GIRARDEAU and JOSEPH BETHENOD, citizens of the Republic of France, and residing at 128 Rue 5 La Boétie, Paris, France, have invented new and useful Improvements in or Relating to Systems for Producing High-Frequency Currents.

For some years past, the development of 10 wireless telegraphy and telephony has been more especially in connection with systems using continuous trains of high frequency waves. Consequently, numerous systems of producing high frequency currents have been 15 proposed, as for instance, Mr. Alexander- 20 son of the General Electric Company having developed special high frequency alter- 25 nators. Such machines are, however, either very expensive in proportion to the output 30 or must be run at an exceedingly high speed in order that a frequency suitable for wireless apparatus may be attained. It is also known that high frequency currents may be produced by the use of arcs or sparks when 35 the arc or spark gap is connected to a suitable circuit, such, for instance, as one containing considerable inductance and capacity 40 connected across the terminals of the arc or spark gaps. In all of these latter systems 45 it has been necessary to put between the discharge gaps and the source of current an ohmic resistance of a somewhat important 50 value, whose purpose is principally to prevent putting the source in short circuit when 55 the arc or spark is produced. The existence of this resistance results in the diminution of the overall electric plant efficiency, as it takes a very important part of the energy 60 provided by the source (50% for example), 65 whatever may be the efficiency of the initial 70 source of electric energy.

As the above mentioned ohmic loss becomes very serious in large plants serving, for instance, wireless telegraphy or tele- 75 80 85 90 95 100 105 110

ony installations the principal object of our invention is to provide a system which will avoid such loss, but which retains the ad- 110 vantageous feature of producing the high frequency oscillations by means of a spark 115 gap.

A further object of our invention resides in the particular arrangement and combi- 120 nation of parts hereinafter described.

In the accompanying drawing:—Figure 1 125 is a diagrammatic view of a simple system embodying our invention. Fig. 2 is a dia-

grammatic view of a somewhat more complicated system than that shown in Fig. 1 but also embodying our invention. Fig. 3 is a diagrammatic view of a third system 60 also embodying our invention, but somewhat more complicated than the system shown in Fig. 2.

Referring more particularly to the drawings:—Fig. 1 illustrates our invention in 65 its simplest form. In the arrangement shown in this figure 2 designates the wires of a supply circuit, one of which is connected to a continuous series motor M which is designed with an unsaturated field. E is 70 a discharge gap, one side of which is connected to the wire containing the motor M, while an inductance L and a capacity or 75 condenser C are shown connected in series across the gap E, the gap together with the capacity and inductance forming an oscillatory circuit for producing high frequency current. Hereafter we shall frequently refer to the circuit E. C. L. in which the energy is used as a discharge circuit. The 80 second wire of the supply circuit is shown as connected to an inductance S from which it leads to the other side of the discharge gap. It will be understood that inductances such as S are commonly connected between 85 the discharge circuit or discharge gap and the supply circuit in order to prevent high frequency oscillations from passing into the supply circuit. Now assuming that the supply circuit Q is connected to a continuous 90 current source, as soon as the discharge gap breaks down and current passes through the motor M a counter electro-motive force will be generated which acts as a real ohmic resistance. Owing to the unsaturated character of the field of the motor as above 95 described, it will possess also a certain inductance. This inductance is, however, not at all prejudicial as it enables us to reduce the value of the self-inductance S which is 100 usually necessary for the purpose above mentioned. As the machine M acts as a motor, it will generate a certain amount of power and this mechanical energy may be disposed of at will and changed back, if 105 desired, into electrical energy again by coupling this machine with one of the generators which supply the discharge gap E.

Referring more particularly to Fig. 2 it will be seen that we have here illustrated one 110 method of carrying out the utilization of power developed by the motor M as just

suggested. In this figure we have combined the motor M with the generating dynamo, so that both of the machines have the same armature, thus saving a collector or commutator. In this figure the discharge circuit E. C. L. remains as before and is connected on one side to the inductance S to the commutator of machine M and on the other side is connected to the commutator of the machine M through the demagnetizing field winding W^1 . The armature of the machine is indicated as I and we have provided a separate exciting circuit, the means of which are indicated by plus and minus, respectively, and connected across which is a field coil W^2 and a variable resistance R similar to that usually placed in series with the fields of generators. It will be seen in this arrangement that the demagnetizing series winding W^1 assumes the same function as the series motor M in the arrangement of Fig. 1, while the whole set serves as a proper generator. It will be seen in this case also that the current supplied to the discharge circuit is of a continuous character. It will be understood also in connection with the arrangement of Fig. 2 that while continuous current generators have previously been used with demagnetizing series field windings that such uses have been in combination entirely different from the present one. It will be understood, moreover, that in the present application the proportion between the ampere turns in the fields W^1 and W^2 , is important as it is necessary that the ampere turns of the winding W^1 be a very important fraction of the ampere turns of the winding W^2 .

Referring more particularly to Fig. 3, we have here shown a system which is particularly designed for use with large plants. In this arrangement the armature is a machine and is excited by a coil W while the discharge circuit E. L. C. and the inductance S is as before. In this arrangement, however, the excitation for the machine M is furnished by a special exciter Z the commutator of which is connected to the opposite ends of the winding W. The coil W^1 is placed in the field of the exciter Z being connected into the armature circuit of the machine M between the commutator thereof and the discharge circuit and is so arranged as to demagnetize the field of the machine Z. The exciter Z is provided also with a field winding W^2 by which its electro-motive force is ordinarily built up so as to bring that of the machine M up to the point where it can produce a discharge across the gap E. The ends of the winding W^2 are connected to any convenient source of continuous current and the usual regulating rheostat R is shown connected in series therewith. It will be noted, however, that when the discharge circuit is supplied from a source of constant

voltage through an ohmic resistance that the voltage supplied to the discharge circuit is decreased in exact proportion to the current being used. Thus if the voltage available at the terminals of the discharge circuit be represented by Z, the voltage of the source by E_0 and the current in the circuit by J, then Z is equal to $E_0 - KJ$, where K is a constant. Since the winding W possesses necessarily a considerable self inductance, the current therein will not vary immediately as the field W^1 varies and consequently the operation of the system would not be as satisfactory as one using an ohmic resistance unless means were provided for overcoming the effects of self inductance. With this end in view we provide a current transformer T the primary of which is connected in series with the armature of the machine M and the coil W^1 so that it will receive the current of the main circuit. The secondary of the transformer T is connected in the armature circuit of the machine Z between said machine and the coil W in such a manner that when there is a sudden rush of current through the main circuit, there will be an electro-motive force generated in the secondary coil of the transformer T which opposes the normal electro-motive force of the machine Z and consequently has the effect of overcoming the result of the self inductance of the coil W. By suitably proportioning the various coils in winding we thus produce a system in which the voltage drop at the terminals of the machine M is directly proportional to the amount of current flow and indeed this result may be demonstrated by certain theoretical considerations which may be expressed mathematically, but which it is believed not to be necessary to set forth. It will be understood, however, that while we have shown and described the preferred form of our invention, that various electrically equivalent elements may be substituted for the parts of the system herein described without departing from the scope of our invention as set forth in the present claims.

What we claim is:

1. The combination with a discharge circuit capable of producing high frequency oscillations, of a continuous current armature connected in series with said discharge circuit, and a coil for coacting with said armature, said coil being so arranged in conjunction with said armature as to decrease the voltage applied to said discharge circuit in proportion to the quantity of current being supplied thereto.

2. The combination with a discharge circuit for producing high frequency oscillation, of an armature for supplying current to said circuit, and a coil for coacting with said armature, said coil connected in series with said discharge circuit and so arranged in conjunction with said armature as to de-

crease the electromotive force of the supply.

3. The combination of a discharge circuit for giving high frequency oscillation, of means for supplying current to said circuit, a coil connected in series to said circuit and said means, and means acting in connection with said coil whereby the electromotive force supplied to said circuit is reduced 10 in proportion to the current supplied thereto.

4. The combination with a discharge circuit, of an armature for supplying current thereto, a field coil for exciting said armature, an exciter armature for supplying current to said field coil, means for exciting said exciter armature, a field coil for said exciter armature connected in series with said discharge circuit and said first men-

tioned armature which is so arranged as to 20 oppose the normal excitation of said exciter armature when current is flowing into said discharge circuit, and a current transformer the primary of which is connected in series with said discharge circuit, said 25 first mentioned armature and said coil and the secondary of which is connected in series to said field winding and said exciter armature, said current transformer being so connected that it opposes the effect of self inductance in said field winding.

In testimony whereof we affix our signatures in presence of two witnesses.

EMILE GIRARDEAU.
JOSEPH BETHENOD.
